UNITED STATES PATENT OFFICE.

ERASTUS E. WINKLEY, OF LYNN, MASSACHUSETTS.

RUBBER-SOLE-ROLLING MACHINE.

1,124,190.

Specification of Letters Patent.

Patented Jan. 5, 1915.

Application filed April 12, 1911. Serial No. 620,573.

To all whom it may concern:

Be it known that I, ERASTUS E. WINKLEY, a citizen of the United States, residing at Lynn, in the county of Essex and State of Massachusetts, have invented certain new and useful Improvements in Rubber-Sole-Rolling Machines; and I do hereby declare the following to be a full, clear, and exact description of the invention, such as will 10 enable others skilled in the art to which it appertains to make and use the same.

The invention relates to a machine for securing the rubber soles to the other parts of the shoe in the manufacture of rubbers, 15 overshoes, rubber boots, or other articles of footwear included under the general term of rubber shoes.

Heretofore in the manufacture of rubber shoes the outsole as well as the lining, upper, insole and other parts of the shoe have been applied to the last by hand, and the outsole has been pressed down upon the insole and shaped to the bottom of the last by a hand roll. In rolling the sole to firmly 20 unite it to the parts beneath it the operator rolls the bottom of the heel, pounds and rolls the heel breast, rolls the shank and forepart, and also rolls over the beveled edge of the sole about its entire margin so 25 that the edge may be united with the upper.

It is the object of the present invention to provide a machine for automatically rolling the soles of rubber shoes in a manner similar to that which is now employed in 30 the hand operation.

To this end the invention consists in the features of construction and combinations of parts hereinafter described and referred to in the claims, the advantages of which 40 will be obvious to those skilled in the art.

The invention will be readily understood from the accompanying drawings and the following detailed description of the machine illustrated therein.

In the drawings Figure 1 is a side elevation of a sole rolling machine having embodied therein the present invention; Fig. 2 is a front elevation on an enlarged scale, the upper portion of the view being continued in Fig. 3; Fig. 4 is a section on the line 4-4 of Fig. 2; Fig. 5 is a detail view of the roll carrying arm, certain parts being as shown in section; Fig. 6 is a front view of the roll carrying arm; Fig. 7 is a partial side elevation on an enlarged scale similar to Fig. 1, the frame being removed

to show the parts beyond; Fig. 8 is a section on the line 8-8 of Fig. 5; Fig. 9 is a section on the line 9-9 of Fig. 1; Fig. 10 is a detail in perspective of a part of the roll actuating mechanism which will be herein-after described. Fig. 11 is a partial side elevation on an enlarged scale, corresponding to Fig. 1, showing only the jack and the adjacent parts of the roll locking device; Fig. 12 is a section through the jack on the line 12-12 of Fig. 11; Fig. 13 is a section on the line 13-13 of Fig. 11; Fig. 14 is a detail in section on the line 14-14 of Fig. 11; Fig. 15 is a detail of the locking device to be herein-after described; Fig. 16 is a section on the line 16-16 of Fig. 11; Fig. 17 is a section on the line 17-17 of Fig. 2; Fig. 18 is a section substantially on the line 18-18 of Fig. 2; Fig. 19 is a section on the line 19-19 of Fig. 18; Fig. 20 is a detail of the auxiliary roll tipping device looking at the opposite side of the machine from that shown in Fig. 1; Figs. 21 and 22 are diagrammatic views of the bottom of a shoe showing the various positions assumed by the roll.

The invention is shown embodied in a machine constructed to operate upon right and left shoes, and provided with two jacks 85 for supporting the lasts to which the parts of the shoe are applied, and with two rolls coöperating with the jacks to roll the soles. The mechanisms for operating the jacks and rolls are to a great extent duplicates, 90 and the mechanisms at but one side of the machine are illustrated, except so far as is necessary to show certain parts of the machine.

The parts of the machine are supported 95 by a frame 1 and a similar frame 2 in line therewith on the opposite side. The parts of the shoe to be operated on are assembled on a last which is carried by a jack 5, and the sole, after being placed in proper position on the bottom of the last, is acted upon by a roll 4 carried by an arm 3. The jack is reciprocated and is also rotated at proper times to cause the roll to act progressively along the surface of the sole and about the 100 edge while the roll is rapidly vibrated and automatically manipulated to secure the proper rolling action on different parts of the sole. At the beginning of the rolling operation the roll is engaged with the center of the heel at the breast. The roll first 105 passes over the heel to the back of the shoe.

It is then shifted laterally to the side of the heel, is given a slight lateral tip, and then rolls toward the breast, as indicated at *a*, Fig. 21. At the breast the roll is shifted laterally to a similar position on the other side of the heel, is given a lateral tip in the opposite direction, and then rolls to the rear of the heel. The roll is then shifted laterally to the center of the heel and rolls toward the toe, drops from the heel to the shank, and rolls the length of the forepart, as shown at *b*. As the roll passes off the toe it drops downward to a limited extent so that it turns down the beveled edge of the sole at this point. The downward movement of the roll at this point is only sufficient to insure proper action upon the extreme point of the toe, and the roll is held in such a position that it will lift itself up on the sole when it travels in the opposite direction, without injury to the shoe. While off the toe the roll is shifted laterally and its lateral inclination changed to conform to the lateral curvature of the sole. The roll now operates over the sole as indicated at *c* to the heel breast, where it is given a still greater lateral inclination and again shifted laterally. As the roll passes from the shank to the ball, the lateral inclination is somewhat reduced to correspond to the variation in the lateral curvature of the sole. The roll now operates toward and rolls off the end of the toe. It is then shifted laterally to the other side of the medial line, and is manipulated to roll the sole on this side in a similar manner. Each time the roll approaches the breast of the heel during the rolling of the forepart and shank the vibration of the roll causes it to hammer the breast. As the roll approaches the toe for the last time, as indicated at *d*, its travel is arrested before it passes off the end of the toe, and it is tipped laterally to an extreme angular position which may be nearly vertical. The jack is rotated through 180°, which causes the roll to travel about the toe and to turn over the beveled edge of the sole and bring it into contact with the upper. The jack is then moved longitudinally to cause the roll to travel along the edge of the shoe while held at an angle, as indicated at *e*, Fig. 22, so that it turns over the edge of the sole. When the roll reaches the breast of the heel its vibration is stopped and the roll is turned at an angle to the longitudinal center line of the shoe, as indicated at *f*, Fig. 22, and is lifted to the tread surface of the heel, so that it turns over the sole edge along the sides of the heel breast. When the roll reaches the tread of the heel it is again vibrated, and at the same time it is turned to a right angle to the center line of the shoe. The longitudinal movement of the jack is then continued until the roll reaches the curved end of the heel, at which

time the jack is rotated 180° to cause the roll to travel about the heel end of the shoe, as indicated at *g*. The other edge of the shoe is rolled in the same manner, the roll passing along the side of the heel, down the heel breast, and nearly to the toe, so that it slightly exceeds a complete circuit of the sole. Here the roll is returned to a horizontal position in the center of the shoe, which passes beneath the roll until it reaches the breast. The roll is lifted up the breast, down again, and up, and then lifted above the shoe, which completes its cycle of operation. The relative movements between the jack and roll described are those which it is preferred to give when using a comparatively short roll which does not reach entirely across the shoe sole. It will be understood, however, that these specific movements and the order in which they are given is not essential, and that some of the movements may be omitted and the order varied without departing from the broader features of the invention. During the rolling over of the edge of the sole along the forepart and shank it is preferred to hold the roll at an inclination transversely of its direction of travel, and to also give the roll an angular vibration as well as a back and forth vibration in the direction of travel. It has been found that this adds to the certainty with which the edge is rolled over and attached to the upper.

The devices for supporting the roll so that it may be automatically manipulated as described are as follows: The roll carrying arm 3 (Figs. 5 and 8) is fixed to a shaft 6 enlarged at one end to form a yoke 7. The yoke is pivoted to swing vertically upon trunnions 8, having bearings in a ring 9. The ring is adapted to rock within the annular frame 10, which may have ball bearings 11. The frame 10 is fixed to a rock shaft 12 which is mounted in a bracket 13 fixed to the frame 1. Below the bracket 13 there is secured to the rock shaft 12 an arm 14 (see Figs. 1, 2 and 5). The outer end of the arm is connected by a universal joint to a rod 15 which is connected by another universal joint to an arm 16 secured to a shaft 17 mounted in bearings on the frames 1 and 2. A lever 18 is also fixed to the shaft and has at its end a cam roll 19 in engagement with a cam 20. Upon rotation of the cam 20 the arm 3 will be swung with the rock shaft 12, and thus the various positions of the roll across the shoe sole may be obtained. The roll 4 (Figs. 5 and 6) is mounted in a fork 21 which is carried by a slide block 22. The block 22 is adapted to slide in ways 23 in the arm 3. A bar 24 connects the block with a lug 25 projecting from a sleeve 26 (Fig. 8) which is held between collars on a shaft 27. The shaft 27 passes through the shaft 6, and at its end (Figs. 1

- and 7) has a universal joint 28 connected to the outer member 29 of a spring coupling. The inner member of the spring coupling is connected by a form 30 to a second fork 31 which engages a slotted segment 32 which is secured to and adapted to rock about a shaft 33. An arm 34 integral with the segment 32 is connected with an arm 35 extending from a strap embracing the eccentric 36.
- 10 The eccentric is secured to a shaft 37 suitably mounted on the frames and having a pulley 38 (Fig. 1) adapted to be driven by a belt from a pulley 39. It will be seen that upon rotation of the eccentric a vibratory movement will be imparted to the roll through the connections described. The spring coupling, which is of the usual telescopic construction, is interposed between the eccentric and the roll so that when the 15 roll strikes against the heel breast the coupling may take up some of the vibratory motion and prevent injury to the heel.
- 15 A vibration controlling device is provided to regulate the amount of vibration above described and, if desired, to stop the vibration entirely during certain parts of the rolling operation. To this end, the fork 31 has mounted on the stud which engages the slotted segment 32, a bar 40, the lower end 20 of which is connected to an arm 41 of a bell crank lever (see Fig. 9). The lever is loosely mounted on a shaft 42 held in bearings on the frames 1 and 2. The other arm 43 of the bell crank carries a cam roll 44 in engagement with a cam path on one side of a cam 45. This cam path is so formed that motion may be imparted to the bar 40 to move the fork 31 on the segment 32 from the dead center in line with the shaft 33 to the end 25 of the segment. This will permit variation, under control of the cam 45, in the vibration of the roll 4 ranging from nothing to the extreme throw at the end of the segment 32.
- 25 Another motion to be imparted to the roll is the side tip to vary the lateral inclination, as indicated in Figs. 21 and 22 at *c*, *d* and *e*. This is produced by turning the ring 9 (Figs. 5, 7 and 8) in the frame 10. The ring has 30 an end wall 46 to which is keyed a pinion 47 in mesh with a gear 48 pinned to a shaft 49. This shaft is mounted in a yoke 50 secured to the frame 10, as is best shown in Figs. 1, 3 and 5. Referring to Fig. 7, the 35 shaft 49 is connected by a universal joint 51 with one member of a telescopic coupling 52, the other member of which is connected by another universal joint 53 to a forked lever 54. This lever is pivoted at one end 40 in line with the universal joint 53 upon a lug 55 depending from a yoke 56 which extends over and across the machine as shown in Figs. 1, 3 and 20. The other end of the lever 54 is engaged by a fork 57 on the upper 45 end of a rod 58. The lower end of the rod

is secured by a universal joint to a lever 59 fixed to a shaft 60 which extends from one side of the machine to the other. It will now be evident from the inspection of Figs. 5 and 7 that if the shaft 60 is rocked, the 70 ring 9 will be turned through the gear connections described, and this turning movement will be imparted directly to the roll 4 by means of the arm 3.

Fig. 20, which is a view similar to Fig. 7, 75 but showing the opposite side of the frame 2, illustrates the actuating means for rocking the shaft 60. It is necessary in order to properly illustrate this mechanism that a small portion of the second sole rolling 80 mechanism be shown. It will be remembered that this is a double or twin machine, and that but one side has been illustrated. Fig. 20 shows the rod 58 and also the lower part of a rod 58^x, the function of which is in 85 every respect similar to the rod 58, and which actuates the roll tipping mechanism on the half of the machine which has been otherwise omitted from the drawings. The rod 58^x is connected to the shaft 60 by 90 means of a lever 61 slotted to receive a pin 62 secured to the rod. The rod extends downward and is joined at 63 to an arm 64 of a bell crank lever mounted on a bracket 65 bolted to the frame 2. The other arm 95 66 of the lever is connected by a rod 67 to a slotted segment 68. The segment is fixed to the shaft 42, which also carries a rigid lever 69 (see Figs. 7, 9 and 20). The lever 69 has a cam roll 70 in engagement with a 100 cam path on the cam 45. This cam path is properly shaped to produce the desired amount of side tip of the roll 4 as it progresses along the shoe. This will ordinarily consist of the positions indicated by *c*, *d* and 105 *e* in Figs. 21 and 23. When rolling the side areas of the sole with the roll in the position *d*, Fig. 21, the lateral angle of the roll is greater at the shank than on the forepart. The angle at the shank will vary in accordance with the style of the shoe being operated upon. In order that various angles may be produced at this point, there is an auxiliary tipping device under control of a cam upon the outside of the machine so that 110 it may be easily removed and another one substituted when the style of the shoe operated upon is changed. The connections between the bar 67 and the segment 68 consist of a block 71 pivoted to the bar. A link 72 joins the block pivot to an ear 73 adjustably secured to a slide bar 74 mounted in bearings 75 on the frame. The slide bar also carries a fixed sleeve 76 which is connected by a link 77 with a block 78 adjustably secured in a T slot in a segment 79. The segment has a stud 80 which extends through a bearing 81 and has fixed thereon a lever 82 in the end of which is carried a roll 115 engaging a cam path in a cam 83. 120

125 130

- Upon rotation of the cam 83 the block 71 will be moved in the segment 68 toward or from the center of oscillation, that is, the shaft 42. The segment 68 is given a uniform movement for all styles of shoes to vary the lateral inclination of the roll 4 at certain times in the operation upon the shoe, and the extent to which the roll 4 is affected by the movement of the segment is varied and controlled by the cam 83 in accordance with the style of the shoe being operated upon. The cam 83 may be readily changed for different styles, as it is on the end of its shaft and outside of the machine. It is not always necessary to change the cam for each style, as the adjustment of the block 78 will often furnish all the variations needed. The cam 83 may be used to produce variations in the side tip of the roll at any desired part of the shoe, as well as at the shank.
- In order that the roll may always exert a pressure toward the shoe, and also to provide means for varying the pressure of the roll upon the shoe, an adjustable spring tension is provided. The ring 9 has a projecting arm 301 (Figs. 3 and 5) which carries, loosely pivoted at its ends, two rods 302. Surrounding the rods and engaged between nuts 303 and ears 304 formed on the hub of the arm 3, are two springs 305. By adjusting the nuts 303 the pressure of the roll may be varied, and this pressure will always be toward the axis of rotation of the arm 3 around the shaft 6.
- Another angular motion imparted to the roll is that for varying the angle of the roll with the longitudinal center line of the sole, which is indicated in Fig. 22 at *e*, *f* and *h*. The mechanism for producing this motion is closely connected with the mechanism for giving the roll an angular vibration. The yoke 21, which carries the roll 4, has a stud 84 (Figs. 5 and 6) which passes through the block 22 and has fixed thereto a bevel gear 85 in mesh with a second gear 86. This gear is mounted on a short shaft journaled in the bearing 87 which is mounted on the slide. A telescopic joint 88 connects the gear shaft with the shaft 89 mounted on the arm 3. The rear end of this shaft has a bevel gear 90 in mesh with a gear segment 91 supported by brackets 92 on the arm 3. A forked arm 93, integral with the segment 91, is provided at its lower end with rolls engaging an annular groove in a spool 94 which is mounted on the shaft 6. The spool is free to slide longitudinally of the shaft, but is connected to rotate therewith by a key. A link 95 is attached at one end to ears on the spool 94 and at the other to the lower end of two levers 96 pivoted on the ring 9. Near the middle of these two levers are two rolls 97 which engage a spool 98 freely mounted on the shaft 27 (see Figs. 8 and 10). The spool 98 is connected by two links 99 with one arm of a bell crank lever 100 which is mounted on brackets formed on the annular frame 10 (Fig. 5). The other arm of the bell crank lever is forked and carries rolls to engage a spool 101 freely mounted on the shaft 12. This spool has a lug 102 which is connected by a link 103 to a similar spool 104 on the lower end of the shaft 12 (Fig. 7). The spool 104 is engaged by rolls carried on one arm of a bell crank lever 105 which is mounted upon a shaft carried by the casting 106 (Figs. 7 and 9). The other arm of the bell crank 105 is connected by a link 107 with a block 108 mounted in a T slot 109 in the slide 110. There is also connected to the block 108 a link 111 which is joined to a lever 112 fixed on a shaft 113. The shaft 113 extends across the rear of the machine and is supported in the bearings carried by the two frames. A lever 114 secured to the shaft 113 has a cam roll 115 in engagement with a cam path on a cam 116. The action of the cam path will move the block 108 up or down in the T slot 109, and as this slot is set at an angle as shown in Fig. 7, a motion will be imparted to the bell crank 105, and through the connections described, to the roll 4, which will be rocked about the stud 84. The telescopic joint 88 is necessary to permit the vibratory motion of the slide which has been described.
- The angular vibration of the roll is produced by the following mechanism: The slide 110 is carried on a rod 117 secured in the casting 106. A link 118 is pivoted at one end to the slide 110, and at the other end is forked to engage a slotted segment 119 which is mounted to oscillate about a pivot 120 also supported by the casting 106. An arm 121 projects from the segment and is connected with an eccentric strap 122 carried by an eccentric 123 mounted on the shaft 37. The position of the link 118 in the slotted segment 119 may be varied by means of a link 124 carried at the end of a lever 125 mounted on the shaft 113. The hub of the lever 125 has a second arm 126 having a cam roll 127 in engagement with a cam path on the cam 116. The levers which are mounted on the shafts 42 and 113 may be yoked across to operate the side of the machine which is not shown in the drawings, as is indicated in Fig. 9. It is apparent that with the link 118 in the position shown in Fig. 7, that is, in line with the pivot 120, no motion will be imparted thereto by the eccentric 123 and the connections described, but as the point of connection between the link 118 and the slotted segment is lifted by means of the cam 116, a varying reciprocating motion will be imparted to the slide 110. This motion will be transmitted through the block 108 to the roll 4, where it is reduced to an oscillation of the roll about its point of con-

tact with the shoe, that is, about the stud 84. While rolling the edge of the sole to secure it to the upper, it is desirable that the higher end of the roll shall be in advance of the lower end, as is indicated by full lines at *e* in Fig. 22. The object of this is that the roll shall have a wiping action to turn the sole over the edge of the shoe. At this time the roll will be oscillating under the action of the eccentric 123, and the axis of the roll will be inclined at its upper end in the direction in which the work is progressing along the shoe, by moving the block 108 above or below its normal position in the slot 109. This is produced by the cam roll 115 and the connections to the link 111, as has been described.

The jack, which has been generally designated by 5, consists of a slide 128 having mounted therein a rod 129, as shown in Figs. 11 and 12. The rod is threaded to engage a sleeve 130 which slides inside the slide 128 and has a finger 131 projecting through a slot in the top of the slide. A second finger 132 is fixed to the slide. By means of a hand wheel 133 on the rod, it may be turned to spread the two fingers 131 and 132 to engage the ends of a slot in the last 134. The slide 128 is mounted in ways on a block 135, which in turn is mounted in ways in the jack carriage 136. The ways for the slide 128 enable the position of the shoe to be adjusted when the work is changed from a small to a large sized shoe. A clamping screw 137 is threaded in a lug on the block 135 to clamp the slide in its adjusted position. Provision is made for rotating the jack to carry the roll around the ends of the shoe by the following construction: The carriage 136, which is preferably formed in two parts held together by bolts 138, has secured to it a ring 139 (Figs. 4 and 17) which has a bearing in a shelf 140 which is secured to the frames of the machine and extends across the front. The lower part of the jack carriage is secured by a pin 141 to a fork on the upper end of a shaft 142, the lower end of which is supported in a bearing carried by a bar 143 extending from one side of the machine to the other. The lower end of the shaft 142 has secured to it a bevel gear 144 which is connected through a second gear 145 with a shaft 146. The shaft 146 is supported in bearings in brackets 147 and 148 (Fig. 2). The shaft has secured thereto a gear 149 which is in mesh with a gear 150 supported upon a shaft 151 supported in bearings on the bracket 148. The construction of the gear 150 is shown particularly in Figs. 18 and 19. The gear is shouldered on the inside to provide bearings for a disk 152 on one side and a plate 153 secured thereto on the other. In a suitable pocket in the disk 152 is mounted a spring pressed pawl 154.

There are a number of notches 161 formed on the inside of the gear 150 to engage the pawl when it is actuated in one direction, that is, if the disk 152 is rocked, the gear 150 will be given an intermittent motion in one direction. The disk 152 has an arm 155 (Figs. 1 and 4) which is connected by a link 156 with a lever 157 having a cam roll 158 (Fig. 1) in engagement with a cam 159. Upon rotation of the cam, the disk 152 will be rocked and an intermittent motion imparted to the gear 150 which is transferred through the connections described to the shaft 142. The distance between the notches in the gear 150 is sufficient to impart a rotary motion of 180° to the shaft 142; that is, the shoe in the position shown in Fig. 1 will be given half a revolution and the toe will then point to the rear of the machine. This motion is provided in order that the heel or the toe of the shoe may pass beneath the roll when it is acting upon the edge of the sole. The reciprocation of the jack below the roll is obtained through a segmental gear 165 mounted on the pin 141 between the sides of the jack carriage. This gear is in mesh with a rack 166 secured to the lower side of the block 135. An arm 167 formed integral with the segmental gear is connected by a link 168 with a spool 169 freely mounted on the shaft 142. The spool 169 is engaged by rolls on a forked arm 170 which is secured to a slotted segment 171 (Figs. 1 and 4). An adjustable block 172 is mounted in the slot of the segment and is pivotally connected with a link 173 joined at 174 to an arm 175 pivoted on a fixed part of the frame. The pivot 174 is also the bearing for a cam roll 176 which is engaged in a suitable cam path on the cam 159. It is apparent that rotation of the cam will rock the segment 171 about its shaft an amount depending on the position of the block 172, and this motion will be transmitted to the segmental gear which will move the block 135 in its ways in the jack carriage.

When the roll leaves the toe of the shoe it should be supported in proper position to again ride up onto the sole when the motion of the jack is reversed. This is accomplished by a mechanism which arrests the downward movement of the roll after it has dropped sufficiently to roll over the edge of the sole at the point of the toe. This mechanism comprises a controlling rod 178 which may be adjusted in accordance with the position of the toe of the shoe operated upon and determines the time of operation of the supporting mechanism. The rod is provided with a laterally projecting finger 177 for engaging the toe of the shoe, and is supported in bearings in a frame 179 (Figs. 11 and 16). The finger 177 may be swung from the horizontal position shown in dotted lines in Fig. 16 toward the shoe, and when in this

position it may be slid in the frame 179 until the finger is at the toe of the shoe. The finger will then be swung to its horizontal position, which will engage teeth 180 on the rod 178 with a rack 181 secured to the frame, thus connecting the rod with the frame. A stop 182 is provided to engage the rack and hold the rod in its horizontal position. The frame 179 is mounted to slide upon a rod 183 which is secured to the frame 1. A link 184 connects the frame with an arm 185 secured to a shaft 186 (Fig. 1) mounted on the frame of the machine. A second arm 187 is secured to the shaft 186 and engages a pin 188 projecting from the forked arm 170. This is indicated in broken lines in Fig. 4. The connections just described between the arm 170 and the frame 179 are such that the frame moves on the rod 183 at the same time and through the same distance that the jack is moved, that is, the rod 178, after being set, will always move so as to remain in the same relation to the shoe. The rear end of the rod 178 will engage a finger 189 when the frame 179 is moved a sufficient distance to the right in Fig. 11. The finger is so arranged that the roll 4 will be at the end of the toe when the rod engages the finger, and will be about to drop from the toe on a continuation of the movement. The finger 189 (Fig. 13) is attached to a valve stem 190 having pistons 191 inside the tube 192. Compressed air from any suitable source is admitted to the tube by a pipe 193, and when the stem 190 is moved to the right the air will pass through the ports 194 into a chamber connected with a pipe 195 which leads to a cylinder 196. The cylinder has a piston 197 with a stem engaging one end of a lever 198 which controls the rod supporting device, (Figs. 14 and 15). The lever is pivoted at 199 on a casting 200 secured to the frame 1. The other end of the lever 198 is connected by a link 201 with toggles 202 which are mounted on the jaws 203 pivoted on the bracket 204. The bracket 204 carries a series of plates 205 which are in sliding contact with plates 206 fixed in a yoke 207 carried by a rod 208. The upper end of the rod 208 is below the arm 3, as shown in Fig. 1, and is always in contact therewith. Therefore, if at the proper time compressed air is admitted to the cylinder 196 the jaws 203 will grip the plates 206, and the rod will be held in its position to support the weight of the arm when the roll passes from the toe of the shoe.

It is desirable that the roll shall have a slight drop when it passes from the toe, to properly roll the sole at the extreme point. Therefore provision is made for a slight lost motion in the supporting device. This is provided by mounting the bracket 204 upon

a stud 209 which is held in a bearing in the casting 200. The bracket has ears 210 which slide upon two rods 211 secured at their lower ends to the casting 200. Springs 212 surround each of these rods and normally hold the brackets and parts of the supporting device carried thereby in the position shown in Fig. 15, but when the weight of the arm and roll is placed on the rod 208, and the jaws are in their clamped position, the bracket will be depressed a slight distance, compressing the springs 212.

In order that the heel breast of the shoe may be rolled, provision is made for actuating the rod 208 to lift the arm and give the roll a vertical motion to operate upon the heel breast, and also to lift the roll clear from the shoe at the completion of the rolling operation. The lower end of the rod 208 is connected with an arm 213 which is rigidly yoked to an arm 214 on the outside of the machine frame (Figs. 1 and 2). These arms are pivoted on the shaft 17 which has been described. The arm 214 has at its end a cam roll 215 in engagement with a disk cam 216. A spring 217 holds the arm 214 away from the cam so far as it is permitted to do so by the position of the arm 3. At the time when the heel breast is to be rolled, projections on the cam 216 will lift or lower the arm 3 to produce the required motion, and at the completion of the work a greater rise will elevate the arm, as shown in Fig. 1.

The main cams of this machine, which have been described, are mounted on the shaft 218, having bearings 219 on the frame 1 and 2. This shaft is driven by a worm gear 220 in engagement with a worm 221 (Figs. 1 and 2) fixed to a shaft 222. The shaft 222 is adapted to be driven from a main driving shaft 223 extending across the rear of the machine and connected by a pair of beveled gears 224 with a sleeve 225 supported in a bearing 226. The worm 221 has a slotted sleeve 227 which is engaged by a similar slotted sleeve 228. A pin 229 fixed in a collar on the sleeve 228 is constructed to engage a slot in a collar on the sleeve 225, thus forming a sliding clutch. When the pin is engaged by the slot, motion will be transmitted from the sleeve 225 to the worm 221. A forked lever 230 engages the sleeve 228 to impart the sliding motion thereto. The lever 230 is held between collars on a shaft 231 which also carries a lug 232. The forward end of the shaft is surrounded by a spring 233, as best shown in Fig. 4, which tends to keep the shaft to the right, that is, with the clutch in engagement. When it is desired to disengage the clutch during the operation of the machine, the operator will depress a treadle 234 pivoted to the machine frame, and through the bell

crank 235 pull the link 236 to the left. The link is secured at its end to the lug 232. This will slide the rod 231 to the left and disengage the clutch. In order to hold the clutch out of engagement there is a latch 237 pivoted to the treadle lever, one end of which will engage a lug 238 on a fixed part of the frame. The latch may be conveniently released by pressing the end near the treadle so that the clutch may be reengaged.

In the usual operation of the machine the cam shaft 218 and the cams thereon would move through a complete rotation to operate upon a shoe. An automatic stopping device is provided to stop the cam shaft after each revolution. This comprises a finger 239 fixed to the cam 116 in position to engage the lug 232 and shift the shaft 231 to disengage the clutch. When the operator wishes to start the machine he will depress the treadle 240 which is fixed to the shaft 231 and adapted to rock the shaft (Fig. 4). This will turn the lug 232 out of the path of the finger 239, as is best shown in Fig. 2, and allow the spring 233 to engage the clutch. After one revolution of the shaft the finger 239 will contact with the lug 232 and thereby disengage the clutch.

While it is preferred to employ the specific construction and arrangement of parts shown and described, it will be understood that this construction and arrangement is not essential, and may be varied or modified without departing from the invention.

Having explained the nature and object of the invention, and specifically described one form of machine in which it may be embodied, what I claim is:—

1. A machine for rolling the soles of shoes, having, in combination, a shoe supporting jack, a roll, and mechanism for relatively actuating the roll and jack to transfer the roll longitudinally over the forepart and vertically over the heel breast of the sole of a rubber shoe supported on the jack, substantially as described.

2. A machine for operating on the soles of shoes, having, in combination, a shoe supporting jack, a tool arranged to turn over the edge of the sole of a rubber shoe supported on the jack, and mechanism for relatively actuating the tool and jack to transfer the tool along the side and around the end of the sole edge, substantially as described.

3. A machine for operating on the soles of shoes, having, in combination, a shoe supporting jack, a tool arranged to turn over the edge of the sole of a rubber shoe supported on the jack, mechanism for moving the jack longitudinally to transfer the tool along the sides of the sole, mechanism for

rotating the jack to transfer the tool around the heel and toe, and mechanism for relatively actuating the tool and jack to transfer the tool along the side edges of the heel breast, substantially as described.

4. A machine for operating on the soles of shoes, having, in combination, a shoe supporting jack, a tool arranged to turn over the edge of the sole of a rubber shoe supported on the jack, mechanism for relatively moving the jack and tool longitudinally of the jack to transfer the tool along the side edges of the sole, mechanism for rotating the jack to transfer the tool around the heel and toe, and mechanism for varying the relative lateral inclination of the tool and jack, substantially as described.

5. A machine for rolling the soles of shoes, having, in combination, a shoe supporting jack, a roll, and mechanism for relatively and automatically actuating the roll and jack to transfer the roll longitudinally of the jack to vary the position of the roll transversely of the jack and to independently vary the relative lateral inclination of the roll and jack, substantially as described.

6. A machine for rolling the soles of shoes, having, in combination, a shoe supporting jack, a roll arranged to turn over the edge of the sole of a rubber shoe supported on the jack, and mechanism for relatively actuating the roll and jack to transfer the roll along the side and around the end of the sole edge, substantially as described.

7. A machine for rolling the soles of shoes, having, in combination, a shoe supporting jack, a roll arranged at an inclination across the edge of the sole of a rubber shoe supported on the jack, mechanism for moving the jack longitudinally to transfer the roll along the sides of the sole, and mechanism for rotating the jack to transfer the roll around the heel and toe, substantially as described.

8. A machine for rolling the soles of shoes, having, in combination, a shoe supporting jack, a roll arranged at an inclination across the edge of the sole of a rubber shoe supported on the jack, mechanism for moving the jack longitudinally to transfer the roll along the sides of the sole, mechanism for rotating the jack to transfer the roll around the heel and toe, and mechanism for relatively actuating the roll and jack to transfer the roll along the side edges of the heel breast, substantially as described.

9. A machine for rolling the soles of shoes, having, in combination, a shoe supporting jack, a roll, mechanism for relatively moving the jack and roll longitudinally of the jack to transfer the roll over the surface of the sole of a shoe supported on the jack and along the side edges of the sole, mechanism

- for rotating the jack to transfer the roll around the heel and toe, and mechanism for varying the relative lateral inclination of the roll and jack, substantially as described.
- 5 10. A machine for rolling the soles of shoes, having, in combination, a shoe supporting jack, a roll, mechanism for relatively moving the jack and roll longitudinally of the jack to transfer the roll over 65
10 the surface of the sole of a shoe supported on the jack and along the side edges of the sole, mechanism for rotating the jack to transfer the roll around the heel and toe, mechanism for varying the relative lateral 70
15 inclination of the roll and jack, and mechanism for varying the angle of the roll with relation to its line of travel along the shoe, substantially as described.
11. A machine for rolling the soles of 20 shoes, having, in combination, a shoe supporting jack, a roll arranged to act on the sole of a shoe carried on the jack, mechanism for relatively moving the jack and roll to transfer the roll longitudinally of the jack, 75
25 and mechanism for automatically varying the angle of the roll with relation to its line of travel along the shoe, substantially as described.
12. A machine for rolling the soles of 30 shoes, having, in combination, a shoe supporting jack, a roll arranged to act on the sole of a shoe carried on the jack, mechanism for relatively moving the jack and roll to transfer the roll longitudinally of the jack, 80
35 and automatic mechanism for oppositely varying the angle of the roll with relation to its line of travel along the shoe when acting on opposite sides of the sole, substantially as described.
- 40 13. A machine for rolling the soles of shoes, having, in combination, a shoe supporting jack and a roll relatively movable to transfer the roll along the sole of a shoe supported on the jack, and mechanism for 85
45 angularly vibrating the roll as it travels along the sole, substantially as described.
14. A machine for rolling the soles of shoes, having, in combination, a shoe supporting jack and a roll relatively movable to 90
50 transfer the roll along the sole of a shoe supported on the jack, mechanism for angularly vibrating the roll as it travels along the sole, and means for varying the amplitude of vibration, substantially as described.
- 55 15. A machine for rolling the soles of shoes, having, in combination, a shoe supporting jack and a roll relatively movable to transfer the roll along the sole of a shoe supported on the jack, and mechanism for 95
60 imparting a to-and-fro vibration and an angular vibration to the roll as it travels along the shoe sole, substantially as described.
16. A machine for rolling the soles of shoes, having, in combination, a shoe sup- 100
65 porting jack and a roll relatively movable to transfer the roll along the sole of a shoe supported on the jack, mechanism for vibrating the roll as it travels along the shoe, and mechanism for interrupting the vibrations at predetermined points in its travel, substantially as described.
17. A machine for rolling the soles of shoes, having, in combination, a shoe supporting jack and a roll relatively movable to transfer the roll along the sole of a shoe supported on the jack, and automatic means for varying the angle of the roll with relation to its line of travel, substantially as described.
18. A machine for rolling the soles of 105
70 shoes, having, in combination, a shoe supporting jack, a roll, mechanism for relatively actuating the roll and jack to transfer the roll along the sole of a shoe supported on the jack, and means for interrupting the transfer of the roll along the sole and for causing a relative vertical movement between the roll and jack to cause the roll to operate upon the heel breast, substantially as described.
19. A machine for rolling the soles of 110
75 shoes, having, in combination, a shoe supporting jack, a roll, means for relatively actuating the roll and jack to transfer the roll longitudinally along the sole and around 90
80 the end of a shoe supported on the jack, a device for supporting the roll, and automatic means for actuating the device when the roll is about to leave the shoe, substantially as described.
20. A machine for rolling the soles of 115
85 shoes, having, in combination, a shoe supporting jack, a roll, means for relatively actuating the roll and jack to transfer the roll longitudinally along the sole of a shoe supported on the jack, a device for supporting the roll, automatic means for actuating the device when the roll is about to leave the shoe, and means for adjusting the actuating means to correspond to the size of shoe 110
90 being operated upon, substantially as described.
21. A machine for rolling the soles of 120
95 shoes, having, in combination, a shoe supporting jack, a roll, an arm carrying the roll, a head on which the arm is pivoted mounted to turn to vary the lateral inclination of the roll, and devices carried by the head for pressing the roll against the shoe carried by the jack, substantially as described.
22. A machine for rolling the soles of 125
100 shoes, having, in combination, a shoe supporting jack and roll relatively movable to transfer the roll along the sole of a shoe carried on the jack, and devices arranged out of the path of the roll for supporting the roll as it passes off the toe in position to

roll up on to the sole when the direction of travel is reversed, substantially as described.

23. A machine for rolling the soles of shoes, having, in combination, a shoe supporting jack and roll relatively movable to transfer the roll along the sole of a shoe carried on the jack, devices for supporting the roll as it passes off the toe in position to roll up on to the sole when the direction of

travel is reversed, and means for actuating said devices as the roll reaches the toe adjustable for different lengths of shoes, substantially as described.

ERASTUS E. WINKLEY.
